Patented Mar. 14, 1922.

FIG. 1.

FIG. 3.

FIG. 5.

FIG. 2.

FIG. 4.

FIG. 6.

INVENTOR:

EDWARD M. McNAMARA,

By *Robert Burns, Atty.*

UNITED STATES PATENT OFFICE.

EDWARD M. McNAMARA, OF CHICAGO, ILLINOIS.

MOP HOLDER AND WRINGER.

1,409,747.

Specification of Letters Patent. Patented Mar. 14, 1922.

Application filed December 23, 1920. Serial No. 432,658.

To all whom it may concern:

Be it known that I, EDWARD M. McNAMARA, a citizen of the United States of America, and a resident of Chicago, in the county of Cook, State of Illinois, have invented certain new and useful Improvements in Mop Holders and Wringers, of which the following is a specification.

This invention relates to that class of household mops in which the structure is adapted to effect a wringing operation of the mopping material in a rapid and convenient manner, and the present improvement has for its objects:—

15 To provide a structural formation and association of the carrying frame and the mop carrying roller, whereby an effective wringing of the mop material is attained.

20 To provide a formation and combination of mop holder parts whereby a durable and effective operative connection between the mop carrying drum is provided, and which provides for a ready detachment of said roller when required.

25 To provide a structural formation of the mop carrying drum whereby the fluid removed in a wringing operation is directed outwardly away from and clear of the mop material, all as will hereinafter more fully appear.

In the accompanying drawing:—

Fig. 1, is a sectional elevation illustrating the preferred construction of the present invention.

35 Fig. 2, is a detail end elevation, with parts in section on line 2—2 Fig. 1, and showing the parts in a wringing position.

40 Fig. 3, is a similar end elevation showing the parts in a position to permit a detachment of the drum or roller.

Fig. 4, is a detail section on line 4—4 Fig. 1.

45 Fig. 5, is an elevation, with parts in section of a modified form of the invention.

Fig. 6, is an end view of the carrying roller of the same.

Like reference numerals indicate like parts in the several views.

Referring to the drawing, 1 designates the frame of the implement formed with a main transverse bar or rail the underside of which is preferably of the arch form shown, with a central socket 2 for the usual mop handle or stick, a transverse bar or member at one

end of said socket, and depending journal 55 ears or extensions 3 for the revoluble support of the mop drum or roller.

4 designates the cylindrical mop drum or roller, which in the present invention is formed with diametrically extending channels 5 in its respective ends. Said channels 5 may be formed directly in the material of the drum when the same has the solid formation illustrated in Figs. 5 and 6, or by means of channel or trough shaped bars 5' secured at the respective ends of the bore of the drum 4 when the same has the tubular form illustrated in Figs. 1, 2, 3, and 4.

6 designates a longitudinal recess or depression formed in the periphery of the drum 4 and either of the concave form shown in Figs. 2 and 3 or the flat form shown in Fig. 6, as may be deemed most desirable. The purpose of said recess is to receive the fold of the mop material 7 at the point of operative connection with the drum 4 and in order that said fold may be in proper relation to the drum to permit an even rolling of the mop material around the drum in a manipulation of parts to effect a wringing of the said mop material.

The means for detachably connecting the drum or roller 4 to the ears 3 of the supporting frame, as well as for effecting a manual rotation of the drum comprises a member 85 having a structural formation as follows:—

8 designates a rod or rail, which when in place, has parallel relation to the periphery of the drum 4 and the longitudinal recess 6 thereof, and adapted to receive the attaching 90 fold of the mop material 7 to hold the same in proper operative connection with the drum.

9 designates right angle extensions at the respective ends of the rod 8 aforesaid, and 95 adapted to engage in the end channels 5 of the drum 4 to attain an operative connection between the parts capable of manual disassociation when required.

10 designates aligned journal portions extending at right angles to the extensions 9 aforesaid, and adapted for revoluble engagement in journals provided therefor on the free ends of the prongs 3 of the supporting frame.

11 designates a lever extending from the outer end of one of the journal portions 10 aforesaid, and provided at its free end with

a handle 11' for convenient manual operation, and with a prong 12 adapted for engagement with a latch member 13 pivotally mounted on the socket portion 2 of the supporting frame, so that when the parts are in a latched condition the lever portion 12 will be held from revoluble movement.

In the present construction the wringing of the mop material 7 is effected by a revolution of the drum 4 to attain a winding up of the mop material upon its periphery, and to carry said material through the restricted space between the periphery of the drum and under edge of the main transverse bar of the supporting frame 1 to attain an effective compressive or squeezing action upon the mop material at such point. In the preferred construction shown in Fig. 2, the forward edge 1' of the transverse bar of the frame 1, is arranged in closer relation to the periphery of the drum 4 than the rear edge 1'' of said transverse bar, so that in a wringing movement of the drum or roller 4 the edge 1' will bear upon the passing mop material and exert a squeezing or squeegee action upon the same to very effectively remove the liquid therefrom. With a turning movement of the drum 4 in a reverse direction, the edge 1' acts to hold the mop material so that the portion of said material between its attaching fold and the edge 1' will bank up and become loosened for effective mopping purposes in confined places.

14 designates a series of orifices formed in the circular wall of the tubular type of drum or roller, and with a view to prevent the flow of the expressed fluid back into the squeezed portion of the mop material 7, said orifices are formed with inturned lips or flanges to constitute dams against such return and cause the liquid to flow out or escape at the ends of the drum.

In the modified construction shown in Fig. 5, the connecting means above described is journalled directly in the end ears 3 of the frame 1 and under ordinary conditions affords satisfactory results in actual use. A yielding connection such as shown in Fig. 1 has been found more desirable however, and comprises an arrangement of parts as follows:

15 designates a pair of bars arranged for sliding movement in the end ears 3 of the frame 1, and provided with journal eyes at their lower ends affording bearings for the aligned journal portions 10 of the connecting means above described.

16 designates a transversely arranged spring attached to the frame 1 with its respective ends engaging the upper ends of the bars 15 aforesaid, and adapted to exert an upward stress upon the same to resiliently force and hold the drum in the direction of the coacting transverse bar of the supporting frame 1.

Having thus fully described my said invention what I claim as new and desire to secure by Letters Patent is:—

1. In a combined mop and wringer, the combination of a frame comprising a central socket, a transverse bar at one end of said socket and depending journal ears at the ends of said bar, a drum revolvably mounted in said ears in operative relation to said transverse bar so that the bar will have direct squeezing action upon the mop material as the drum is rotated, means for connecting the mop material to the drum, and means for imparting rotation to the drum. 70

2. In a combined mop and wringer, the combination of a frame having a transverse bar and end prongs, a tubular drum revolvably associated with said prongs in operative relation to said transverse bar and having inwardly flanged orifices in its circular wall, means for connecting the mop material to the periphery of said drum, and manual means for imparting rotation to said drum. 85

3. In a combined mop and wringer, the combination of a frame having a transverse bar and end prongs, a drum revolvably associated with said prongs in operative relation to said transverse bar and having diametric channels formed in its respective ends, a connecting means between the frame and drum comprising a longitudinal rod having adjacent relation to the periphery of the drum and providing an attaching means for the mop material, angular extensions at the respective ends of said rod adapted for engagement in the aforesaid end channels of the drum, journal portions extending at right angles from said extensions, and an operating lever attached to one of said journal portions. 95

4. In a combined mop and wringer, the combination of a frame having a transverse bar and end prongs, a drum revolvably associated with said prongs in operative relation to said transverse bar and having diametric channels in its respective ends formed by channel shaped bars arranged in the interior of the drum, a connecting means between the frame and the drum comprising a longitudinal rod having adjacent relation to the periphery of the drum and providing an attaching means for the mop material, angular extensions at the respective ends of said rod adapted for engagement in the aforesaid end channels of the drum, journal portions extending at right angles from said extensions, and an operating lever attached to one of said journal extensions. 110

5. In a combined mop and wringer, the combination of a frame having a transverse bar and end prongs, a drum revolvably associated with said prongs in operative relation to said transverse bar and having dia- 120

- metric channels formed in its respective ends, a connecting means between the frame and drum comprising a longitudinal rod having adjacent relation to the periphery 5 of the drum and providing an attaching means for the mop material, angular extensions at the respective ends of said rod adapted for engagement in the aforesaid end channels of the drum, journal portions 10 extending at right angles from side extensions, an operating lever attached to one of said journal extensions, and a latch member attached to the frame and adapted for engagement with said lever.
- 15 6. In a combined mop and wringer, the combination of a frame comprising a central socket, a transverse bar at one end of said socket and depending journal ears at the ends of said bar, a drum revolvably mounted 20 in said ears in operative relation to said transverse bar so that the bar will have direct squeezing action upon the mop material as the drum is rotated, means for connecting the mop material to the drum, 25 and means for imparting rotation to the drum, the aforesaid transverse bar having an arched form next adjacent to the drum and adapted to effect increased squeezing pressure on the side portions of the mop 30 material as said drum is rotated.
7. In a combined mop and wringer, the combination of a frame having a transverse bar and end prongs, sliding bars mounted in said prongs and having journal eyes at their lower ends, a spring tending to move 35 said bars in one direction, a drum arranged between the prongs aforesaid in operative relation to said transverse bar and having diametric channels formed in its respective ends, a connecting means between the frame 40 and drum comprising a longitudinal rod having adjacent relation to the periphery of the drum and providing an attaching means for the mop material, angular extensions at the respective ends of said rod adapted for 45 engagement in the aforesaid end channels of the drum, journal portions extending at right angles from said extensions, and an operating lever attached to one of said journal portions. 50
8. In a combined mop and wringer, the combination of a frame comprising a central socket, a transverse bar at one end of said socket and depending journal ears at the ends of said bar, a drum revolvably mounted 55 in said ears in operative relation to said transverse bar so that the bar will have direct squeezing action upon the mop material as the drum is rotated, said drum having a longitudinal recess in its periphery, a longitudinally extending rod associated with said recess for holding the mop material in place, and means for imparting rotation to the drum. 60

Signed at Chicago, Illinois, this 18th the 95 day of December, 1920.

EDWARD M. McNAMARA.
